KNITTING MACHINE

Max C. Miller, Cumberland, R. I.

Application March 9, 1932, Serial No. 597,743

7 Claims. (Cl. 66—96)

The present invention relates to knitting machines, and is herein disclosed as specifically embodied in a flat full-fashioned cotton type machine.

The primary object of the present invention is to provide a machine for knitting non-run loop fabric having the general characteristics of the fabric described in the co-pending application of the present applicant Serial No. 594,834, filed February 24, 1932, for Knitted fabric and method of producing the same.

More specifically it is an object of the invention to provide a knitting machine which is adapted for knitting designated courses to cause a plurality of needle loops of a course to be drawn through a single loop of a preceding course, so that each of the single loops treated in this manner will be supported, as additional courses of the fabric are knitted, by two or more series of loops forming separate fabric wales.

Another object of the invention is to provide mechanism of this general description which is readily applicable to existing types of machine, and operates to lift and spread designated needle loops over a plurality of needles, so that each of the loops formed by these needles on the next succeeding course, will be drawn through the same loop.

Another object of the invention is to provide novel and improved instrumentalities for handling yarn, which while particularly adapted for use in connection with the flat Cotton type machine herein disclosed for knitting non-run looped fabric, are well adapted for use in other types of machines, and for knitting other types of fabric.

With these and other objects in view, as may hereinafter appear, a principal feature of the invention consists in the provision of a loop lifting mechanism which is arranged to engage with and lift designated needle loops from the needles, and to spread these loops over a plurality of needles, so that each of the loops taken by these needles in the next succeeding course of knitting, will be drawn through the spread loops.

Another feature of the invention consists in the provision of novel and improved loop lifting instrumentalities comprising loop lifting points which are simple and sturdy in construction, economical of space, and readily mounted in the support to secure a firm and accurately aligned assembly of the points.

The several features of the invention consist also in the devices, combinations and arrangement of parts hereinafter described and claimed

which, together with the advantages to be obtained thereby will be readily understood by one skilled in the art from the following description taken in connection with the accompanying drawings, in which Fig. 1 is an end view cross section of a part of a flat full-fashioned Cotton type machine with the new mechanism applied thereto; Fig. 2 is a front view elevation of Fig. 1; Fig. 3 is an end view cross section of the machine with various parts omitted to illustrate particularly the control mechanism for the loop lifting and spreading mechanism; Fig. 4 is a detail view in front elevation of the cam controlling the position of the loop lifting points lengthwise of the machine, as shown in Fig. 3; Fig. 5 is a diagrammatic view showing the development of the cam in Fig. 4; Fig. 6 is an enlarged end view of the cooperating point bars used in the new structure; Fig. 7 is a sectional view of the points taken on the line 7—7 of Fig. 6; Fig. 8 is a diagrammatic drawing of the fabric on the needles at the time both sets of points are in engagement with their respective needles and their loops; Fig. 9 is a diagrammatic drawing of the fabric on the needles with the smaller points remaining in engagement with their cooperating needles as the larger points are drawn away from the needles prior to being shifted endwise; Fig. 10 is a diagrammatic drawing of the fabric on the needles showing the small set of points still in engagement with their respective needles, and with the larger points shifted sideways and co-acting with adjoining needles; Fig. 11 is an end view illustrating a preferred form of loop lifting point and the supporting bar; Fig. 12 is a partial section taken on the line 12—12 of Fig. 11 showing the point grooves in the point support bar; Fig. 13 is an enlarged detail view in side elevation of the new loop lifting point; Fig. 14 is a front elevation of the point shown in Fig. 13; Fig. 15 is a cross section taken on the line 15—15 of Fig. 13; and Fig. 16 is a section taken on the line 16—16 of Fig. 13.

As illustrated in the drawings, the invention is disclosed in a preferred form as applied to a flat full-fashioned Cotton type knitting machine provided with a narrowing machine attachment of ordinary description and arranged to have the ordinary mode of operation of these machines. In carrying out the invention, mechanism has been provided which is arranged to transfer a portion of each of certain needle wale loops to adjoining needles while retaining the other portion of such loops on the needles on which they were formed. This mechanism comprises a set of loop lifting elements which may be similar to the ordinary

picot bar utilized on these machines, and an additional set of loop lifting elements which are arranged to cooperate therewith. The two sets of points are arranged to engage with each other 5 and with the needles, so that the needle loops will be cast off from the needles onto the superimposed points, one set then being moved relatively to the other to register these points with adjacent needles, thus causing the loops to be spread over 10 two needles, so that two needle loops of the next succeeding course will be drawn through each one of the spread loops.

In the drawings, the needles are indicated at 1, the needle bed for supporting the needles at 2, 15 the sinkers at 3, the catch bar at 4, the fixed pressing surfaces at 5, and the sinker head support at 6. A narrowing machine of ordinary construction is provided which comprises the usual narrowing machine rod 7 carried on the arms 8 20 pivotally mounted on a rod 9 on the rear side of the machine. Secured to the rod 7 are the hangers 10 carrying the bars 11 and 12 to which are fastened the narrowing point units 13 and 14 in accordance with the usual practice. The rod 7 is 25 also provided with brackets arranged to receive the picot rod 15 which carries pivotally mounted thereon the hangers 16 rigidly secured at their lower ends to the picot bar 17 on which are fastened the picot points 18. The picot bar 17 is 30 rigidly secured in operative position to turn with the rod 7, or can be moved relatively thereto and latched out of operative position by means of a spring-pressed plunger 19 mounted in a bracket 35 20 secured to the rod 7, and arranged to engage alternatively with two slots 21 or 22 in the face of a disk-shaped extension 23 formed on one of the hangers 16.

The entire narrowing machine assembly mounted on the arms 8 is supported in the usual manner 40 by a vertical link 24 secured at its upper end to a bracket on the rod 7, and at its lower end connected to a laterally extending cam lever arm 25 which is pivoted at 26 on the machine frame, and is provided intermediate its length with a cam roll 45 a arranged normally to ride on an idler roll on the cam shaft 27 for the machine, and when rendered operative by the usual lengthwise shifting of the shaft, to engage with its actuating cam a'. Inasmuch as the movements imparted to the narrowing machine by the cam a' and the cooperating movements of the needles during the operation of the narrowing machine and the relative timing of these elements are preferably the same 50 as normally employed in machines of this description, further illustration of the movements imparted to the narrowing machine as a whole and the needle movements cooperating therewith, is believed unnecessary, and has been omitted.

The new mechanism consists of the arms 28 60 supporting the new point control rod 29, to which is fastened for swinging movement the arms 30 which form a rigid part of the new point bar 31 and to which are fastened the points 32. There are further provided the spring plunger supports 33, rigidly fastened to the rod 29 and fitted with a spring plunger 34 which engages either in the notch 35 or 36, the former for locking the points in the working position and the latter for holding them swung upwardly in their idle position. There is further rigidly fastened to the rod 29 a depending lever 37 which is fitted at its lower end with a pin 38, said pin working freely in the arcuate slot 39, the center of the radius of this slot being 70 75 the fulcrum center 9 of the narrowing machine.

arms 8, so that upon normal up and down movement of the narrowing machine, no in and out movement need be transmitted to the points 32. The arcuate slot 39 is formed in the lever 40 which is rigidly fastened to a shaft 41 extending 5 throughout the machine length, said shaft having fastened to it, at some portion of its length, a lever 42 which is provided at its lower end with a cam roll c arranged to engage with an idler cam on the main cam shaft 27 of the machine. Inasmuch as the inner points 32 with the mode of operation of the parts herein set forth are given a simple arcuate movement about the pivot shaft 9 of the narrowing machine, and are brought into and out of engagement with the needles by the 15 usual in and out movements imparted to the needle bar during the operation of the narrowing mechanism, the shaft 41 and lever 42 are maintained at all times in a constant position, the idler cam engaging the roll c, being arranged for this purpose to maintain its engaging contact therewith when the cam shaft 27 is shifted endwise in the usual manner to bring the narrowing machine into operation. A tension spring acts on the lever 42 to maintain the roll c in engaging contact with its cam. At its upper end the slot 39 is cut away at one side, so that with the parts as shown in Fig. 1, the lever 37 and roll 38 may be disconnected therefrom and moved in a counter-clockwise direction to swing the point bar 29 upwardly to inoperative position where it is held by the engagement of the spring plunger 34 with the notch 36.

The new mechanism also consists in the addition of a lever 45 which is rigidly fastened to the present picot rod 15, and is provided at its lower end with a pin 46 arranged to engage in an arcuate slot 47 formed in the upper end of a lever 48 secured to a shaft 49 which extends throughout the length of the machine. The angular position of the shaft 49 and lever 48 are determined by means of a cam lever 50 which is provided at its lower end with a roll b arranged to engage during the operation of the narrowing device with a corresponding cam b' on the cam shaft 27. A spring 51 is arranged to maintain the lever 50 and roll b in contact with its cam b'. These parts for controlling the position of the points 18 are similar in their construction and operation to those described for controlling the position of the points 32, and are arranged for the normal position of the control lever 48 illustrated in Fig. 1, to impart an arcuate movement to the points about the pivot of the links 8 on which the narrowing machine is supported. The cam b' as hereinafter more fully pointed out, is designed to impart a rocking movement to the shaft 49 and lever 48 at a predetermined point in the cycle of operation of the narrow machine, to rock the picot rod 15 and move the loop lifting points 18 rearwardly out of engagement with the points 32, so that the points 18 may be racked lengthwise of the needle series, and thereafter to advance them into engaging contact with the next adjacent needles.

While with the construction set forth in the drawings the control lever 48 is controlled in a single position by the operation of the roll c to maintain a constant angular position of the point control rod 29 with relation to the narrowing machine frame, it will readily be seen that this mechanism could be adapted to provide a forward and back movement of the points 32, and thus permit a modification of the movements now im- 75

parted to the points 18 for engaging and disengaging the two sets of points. The mechanism above described has the further advantage of providing a particularly sturdy construction which 5 may be readily adjusted to the extreme accuracy required in fine gauge machines.

Movements lengthwise of the needle series are imparted to the loop lifting points 18 and 32 by means of a shifting cam disk 54 (see Figs. 3, 4 10 and 5) loosely mounted to turn on the narrowing machine rod 7, and provided on one face thereof with two surface cams 55 and 56 arranged to engage with the ends respectively of the bars 29 and 15 which are held yieldingly in engagement with the cam by spring means of ordinary description not here shown. The cam disk 54 is actuated in timed relation to the operation of the narrowing machine to produce the required positioning movements of the points 20 lengthwise of the needle series by means of a ratchet 57 formed on the periphery of the disk 54, and a pawl 58 arranged to engage therewith and supported on a short arm 59 pivoted to the shaft 7. Movement is imparted to the pawl to give 25 a step-by-step advance to the disk 54 through connections which include a link 60 connected at one end to the pawl arm 59 and at its other end to the upwardly extending arm of a cam lever 61 pivoted on the shaft 9, and at its lower 30 end provided with a cam roll *d* which is arranged during the narrowing operation to ride on a corresponding cam *d'* on the cam shaft 27. During the normal operation of the machine, the roll *d* rides on an idler cam adjacent to the cam *d'*, being transferred to the cam *d'* by the endwise 35 shifting of the cam shaft to throw the narrowing machine into operation. A spring 62 is connected to the lower end of the cam lever 61, and tends to maintain the roll *d* at all times in engagement with its cam.

Figs. 11 to 16 inclusive of the drawings, illustrate a preferred form of loop lifting point which is particularly adapted for use in carrying out the present invention, although it may be applied 45 to advantage in knitting machines generally for lifting and transferring loops from the needles. The ordinary point or loop lifting implement commonly used on cotton machines which is formed of a round piece of wire with a butt offset at 50 approximately right angles to the shanks, and with the lower or needle engaging portion milled or die-struck to form a groove for engaging the needle, has certain imperfections which while not greatly interfering with its practical use in 55 present day machines, become of great importance when the implement is utilized in connection with the mechanism herein disclosed for registering accurately two sets of points with each other and with the needles.

60 While the art of milling, striking, coin stamping or otherwise forming the groove of these points has been developed to a remarkable degree of accuracy, it is nevertheless difficult to assure that the grooves are absolutely central 65 with the outer portion of the shank of the points. It is also impractical to have the groove of nearly the point width, for by so doing the edges of the groove break down and present rough surfaces against which the yarn of the loops will later 70 be cut or otherwise disturbed.

The present method of mounting points in their supports is to drill small holes in the supports, in which the butts of the points are placed. The drilling of these holes is expensive, due to their 75 extremely small diameter, and in many cases re-

sults in the running off or disalignment of the drill, so that when a point is later inserted in this out-of-square hole, the point is twisted, which makes it difficult for later alignment with any needle with which it later may be associated. 5 Also in the bending of the butt of the point, it sometimes happens that the bending is not parallel to the point groove which will cause the point to be twisted when it is inserted in its support.

The new point is produced from thin, flat 10 stock which insures the groove being the full width of the point (less the wall thickness), the width being held very accurately due to the use of flat stock. Further, the inside of the groove will, by the very nature of the method of production, be smooth. 15

Instead of drilling holes in the point support, the new invention contemplates bending a part 20 of the stock of which the point is made at right angles to the shank and entering this bent portion into a groove cut into the point support at right angles to the point grooves. To hold this new point from turning, the upper shank of the point, instead of being formed in the ordinary U section will be formed V shaped, so that 25 this portion of the shank will fit into the V grooves ordinarily cut into the point supporting member.

As shown in Figs. 11 to 16 inclusive, the point support or bar is indicated at 64, and is provided 30 with a narrow slot 66 running lengthwise of the support to receive the offset butts 67 of the points, and V-shaped grooves 68 to receive the correspondingly V-shaped shank portions 69 of the points. The points are clamped in position in 35 the support by means of a cover plate 70 and clamping screw 72. The needle engaging portion of the point indicated at 74 is bent or molded into a semi-circular shape (as shown in Fig. 16), so that the points will fit snugly about the needles, 40 and may be placed one within another as shown in Fig. 7 to take up the least possible amount of space and permit the needle loop to be readily cast off from the needle onto the point.

In operation, the mechanism functions as follows: 45

As is customary in the present cotton machine construction, and as previously explained, the new point bar can be swung from its idle position into the position shown in Fig. 1, the regular picot bar 17 having previously been swung 50 into its active position so that the narrower point 32, due to the end control mechanism of the rods 15 and 29, can be aligned and buried in the picot points as shown in Figs. 1 and 6, the spring plungers 19 and 34 effectively holding the points in this position, with the pins 46 and 38 holding the points in this relationship during the downward movement of the narrowing machine from 55 the position shown in Fig. 1.

The points so locked into each other now move 60 downward as in the present well-known loop-lifting movement and engage with their respective needles as shown in Fig. 8, and when so engaged move downward with the needles until the needles, with which the points are associated, 65 cast off their loops onto the points, after which the points and needles move upwardly until the ends of the points are above the knockover bits, all of these movements being the same as is 70 customary in any loop-lifting operation in full-fashioned machines. Thereafter, the points 18 move away from the points 32, stretching their loops as shown in Fig. 9, this movement being sufficient to then permit the points 18 to move 75

sideways, as shown in Fig. 10, and when they are in this position, they can be engaged with the needles in the new setting and thereafter the loop-lifting implements move downward with the needles in the regular manner, having thereby transferred to adjoining needles a portion of the needle wale loops with which they were associated. The entire narrowing assembly then moves upwardly into the position shown in Fig. 1 as is customary with this type of machinery, remaining in this position until the next loop-shifting operation, which may take place on the same needles or adjoining needles, and due to the endwise shiftability of the rods 15 and 29, may be either to the right or to the left depending on the contours of the face cams 55 and 56, thereby making it possible to produce a great variety of fabric structures and all of the structures shown in the copending fabric application above referred to.

Assuming that the machine has finished a plain course of fabric, and it is desired to transpose the loops of this course, the cam shaft shifts, when the roller *a* of the narrowing machine reaches the position *x*, Fig. 3, thereby aligning the narrowing machine rollers *a* with their cams *a'*, as well as aligning the *d'* cam with its roller *d* and the *b'* cam with its roller *b*, the *d* roller being part of the ratchet mechanism, while the *b* roller controls the movement of the lever 48.

We will assume that prior to the shift, the thick and thin points are in line with each other and aligned with needles *X*, Fig. 8, the point bar rods 29 and 15 being against their shifting cams, as shown in Figs. 4 and 5.

Continued rotation of the cam shaft will lower the narrowing machine, the thick and thin points simultaneously engaging with their needles, as shown in Fig. 8. The narrowing machine continues downward and then upward until the roller *a* reaches the *A* position of its cam, Fig. 3, which is at the time the points are clear of the knock-over bits, ready to be shifted. All shifting must take place between *A* and *A'*, Fig. 3, as between these points the narrowing cam is radial and holds the narrowing machine with the points just above the knockover bits.

At the time the narrowing machine roller *a* is opposite the *A* portion of its cam, the *b* roller which controls the shaft 49 with its levers 48, is opposite its *B1* position. As the cam shaft now continues to rotate, the roller *b* moving down the decline of its cam to *B2*, moves the levers 48 in a direction toward the left, Fig. 1, and as these levers control the levers 45, the large points 18 will be caused to move away from the narrowing points 32 as shown in Fig. 9 and dotted lines in Fig. 6, the points remaining in this separated position while the cam shaft moves from *B2* to *B3*. It is while the points are so separated that the roller *d* in moving to the position *D3* of the cam shaft rides up its cam incline and thereby causes a racking of the drum, a shifting of the rod 15 one index to the right, as shown in Fig. 5, and the aligning of the wide points 18 with the needles *Y*, Fig. 8. The movement of the rods in relation to the cam is from 1 to 2 (Fig. 5), the rod 29 not being shifted.

At the end of this shifting movement of the rods 15 and 29, with the *d* roller on the top of its *D3* rises, the roller *b* is on the low portion of its cam at *B3*, the points 18 being away from the needles as shown in Fig. 9, but shifted from the *X* to the *Y* needles. Upon further rotation of

the cam shaft the *b* roller will rise up its incline at *B3* and thereby move the points 18 toward the needles, as shown in Fig. 10. By this time, the narrowing machine roller *a* has reached the *A'* position, so that immediately thereafter the narrowing machine goes down, followed by an up movement.

When the narrowing machine rollers *a* reach the *x'* position, at which time the end of the points are again just above the knockover bits and are therefore be shifted sideways, the rollers *b* are at the *B4* position, continued movement of the cam shaft causing these rollers to move down their cam decline and in this manner move the points 18 away from the points 32 to a position similar to that shown in Fig. 9. As soon as the points are so separated, the roller *d* rises up its *D5* incline, thereby racking the shifting mechanism for the rods 15 and 29, moving these rods into their position 3, Fig. 5. The rod 29 which controls the points 32, moves to the left, so that these points will in the next loop shifting movement contact with *Y* instead of *X* needles, while the rod 15 moves to the left two indexes, thereby causing the respective points 18 to align with their points 32, both points being in line with each other as shown in Fig. 9, only being aligned with *Y* needles instead of *X* needles.

Continued rotation of the cam shaft past the *B5* position will cause the *b* rollers to lock the points together, as shown in Figs. 6 and 7, ready for the next loop shifting movement. The just described in and out and sidewise movement of the points has taken place between the *x'* and the *x* position marked on the narrowing cam, Fig. 3. The cam shaft is shifted endwise again at the *x* position so that one or more courses of plain knitting can take place.

The nature and scope of the invention having been indicated, and a machine embodying the several features of the invention having been specifically described, what is claimed is:

1. In a flat knitting machine, the combination with a series of needles and their cooperating knitting elements, of a cam shaft for the machine, a narrowing machine frame actuated from said cam shaft to move toward and away from the needles in a line substantially lengthwise of the needles, a series of loop lifting points, a support for said points pivotally mounted on the frame, and a stationary guiding member, said support and guiding member having cooperating cam and follower surfaces for determining the angular position of said support and points mounted thereon during the movement of said frame. 55

2. In a flat knitting machine, the combination with a series of needles and their cooperating knitting elements, of a narrowing machine frame movable toward and away from the needles in a line substantially lengthwise of the needles, a series of loop lifting points, a support for said points pivotally mounted on the frame, a guiding member arranged to turn about a stationary pivot, said support and guiding member having cooperating cam and follower surfaces for determining the angular position of said support and points mounted thereon during the movement of said frame, and means controlled from said cam shaft for determining the angular position of said guiding member during the movement of said frame. 70

3. In a flat knitting machine, the combination with a series of needles and their cooperating knitting elements, of a narrowing machine frame movable toward and away from the needles in a 75

line substantially lengthwise of the needles, a series of loop lifting points, a support for said points pivotally mounted on the frame, and a stationary cam engaging with said support to control the angular position of the support and points mounted thereon during the movements of the narrowing frame toward and away from the needles.

4. In a flat knitting machine having a series of needles and cooperating knitting elements, a narrowing machine frame supported to swing about a stationary pivot, a plurality of loop engaging point holders pivotally supported thereon, downwardly extending arms connected to swing with said holders about their pivotal mounting on the narrowing frame, cooperating upwardly extending guide levers pivoted on a fixed portion of the machine frame, cam and follower surfaces formed respectively on each of said arms and cooperating guide levers to control the forward and back position of the points during up and down movements thereof with the frame, and means for controlling the angular position of said guide levers including means for moving one of said guide levers to vary the forward and back position of the points controlled thereby with relation to the needles.

5. In a flat knitting machine having a series of needles and cooperating knitting elements, a loop engaging point holder, a frame on which said holder is pivotally mounted, said frame having a pivotal mounting to permit movement of the holder toward and away from the needles longitudinally of the needle shanks, a lever arm connected to swing with the holder about its pivot, and an upwardly extending guide lever supported on a fixed portion of the machine and having a guiding groove arranged for engagement

with a follower surface on said lever arm to control the forward and back position of the holder during up and down movements of the frame.

6. In a flat knitting machine having a series of needles and cooperating knitting elements, a loop engaging point holder, a frame on which said holder is pivotally mounted, said frame having a pivotal mounting to permit movement of the holder toward and away from the needles longitudinally of the needle shanks, a lever arm connected to swing with the holder about its pivot, an upwardly extending guide lever supported on a fixed portion of the machine and having a guiding groove arranged for engagement with a follower on said lever arm to control the forward-and-back position of the holder during up-and-down movements of the frame, and means for moving the guide lever about its pivot to vary the forward and back position of the points with relation to the needles. 20

7. In a flat knitting machine having a series of needles and cooperating knitting elements, a loop engaging point holder, a frame comprising a rock shaft on which said holder is supported and in turn supported to move about a fixed pivot to 25 raise and lower the holder with relation to the needles, a downwardly extending lever secured to the rock shaft, an upwardly extending guide lever pivotally supported on a stationary portion of the machine, said lever arm and guide 30 lever having cooperating cam and follower surfaces to control the forward and back position of the holder and points during vertical movements thereof with the frame, and means for maintaining said holder yieldingly in one of two 35 alternate operative and inoperative positions on said rock shaft.

MAX C. MILLER.
